UNITED STATES PATENT OFFICE

DONALD S. BARROWS, OF ROCHESTER, NEW YORK

RAILWAY TRUCK

Application filed February 23, 1928. Serial No. 256,332.

This invention relates to railway trucks and more particularly to the construction of the side frames, bolster and associated parts whereby lateral motion is permitted between 5 the bolster and side frames as well as, if desired, rocking between the bolster and side frames in vertical longitudinal planes.

The principal object of my invention, generally considered, is the improvement in car 10 trucks for increasing the flexibility thereof by permitting lateral motion of the bolster as well as angling between the side frames and bolster in longitudinal vertical planes whereby such trucks have the desired flexibility for 15 accommodating themselves to inequalities and curves in the track and for relieving the members thereof from sudden and undue strains, thereby increasing the life of such trucks.

20 An object of my invention is the provision of railway trucks formed with side frames having bolster openings receiving springs and spring caps, said spring caps having pockets in the spaces immediately adjacent 25 and between the bolster guide columns, said pockets being provided with depressed rocker bearings, rockers operating in said pockets and supported on said bearings and a bolster supported on said rockers for lateral movement 30 with respect to said frames, said rockers being preferably so designed that the bolster raises upon movement outwardly on the rockers and is retained at a substantially constant elevation when moved inwardly.

35 Another object of my invention is the provision of railway trucks formed with side frames having bolster openings receiving springs and spring caps, said spring caps being desirably formed as a spring supported 40 portion curved or crowned on its upper surface and a rocker supporting portion, said latter portion being designed to rock in a vertical longitudinal plane on the spring supported portion and formed with depressed

45 pockets carrying segmental rockers, and a bolster carried on said rockers for lateral motion with respect to said frames, said bolster being preferably formed with pockets to receive the upper ends of said rockers and 50 provided with means interlocking with said

rockers whereby the proper relative positions of the parts are maintained.

A further object of my invention is to provide a railway truck formed with side frames having tension and compression members, 55 bolster guide columns connecting the intermediate portions of said tension and compression members, springs supported by said side frames between said guide columns, spring caps supported on said springs, said spring caps being formed with bearings for lateral motion rockers, rockers resting on said bearings, said rockers being generally triangular and placed point down in said spring caps in order that the spring cap load shall remain substantially on the center line of the spring group, the upper portions of said rockers presenting a curved rocking surface for supporting an associated bolster, said bolster being formed with upwardly inset bearings and 60 interlocking lugs engaging said rockers for preventing slippage therebetween, said rockers being formed to raise the bolster when moved outwardly and maintain said bolster at the same elevation when moved inwardly 65 whereby said bolster is self-centered.

A still further object of my invention is to provide an integral side frame formed with a bolster opening, springs supported in said opening, a spring cap on said springs, lateral motion rockers supported by means of said spring cap and a bolster resting on said rockers, said bolster spring cap and rockers therebetween being supported in the frame so that angling with respect to said 80 frame in a vertical longitudinal plane is also permitted thereby providing flexibility longitudinally as well as transversely of said frame.

Other objects and advantages of the invention relating to the particular arrangement and construction of the various parts will become apparent as the description proceeds.

Referring to the drawings illustrating 95 my invention, the scope whereof is defined by the appended claims,—

Figure 1 is a partial side elevation of a railway truck particularly showing the intermediate portions of the compression and 100

tension members of a side frame, the connecting bolster guide columns, the end of the bolster and the associated connecting parts.

Figure 2 is a transverse sectional view of the frame shown in Figure 1, the associated bolster and spring cap being shown in side elevation.

Figure 3 is a fragmentary view corresponding to Figure 2 but showing the spring cap in transverse section and omitting the lower portion of the frame.

Figure 4 is a plan of the spring cap shown partly in horizontal section with the rockers thereof shown in horizontal section.

Figure 5 is a fragmentary view corresponding to Figure 1 but showing a modification.

Figure 6 is a side elevational view of the bolster and spring cap illustrated in Figure 5 shown partially in section on the line 6-6 of Figure 5, looking in the direction of the arrows.

Figure 7 is a half plan of the spring cap shown in Figure 6, with a rocker in place.

Figure 8 is a fragmentary side elevation of a truck, said view corresponding to Figure 1 but showing a further modification.

Figure 9 is a transverse sectional view of the construction shown in Figure 8, the associated bolster and spring cap being shown in side elevation.

Figure 10 is a plan of the spring cap shown in Figure 9.

Referring to the drawings in detail, like parts being designated by like reference characters, and first considering the embodiment of my invention illustrated in Figures 1 to 4, inclusive, there is shown a portion of a truck comprising a side frame 1 formed with a compression member 2, a tension member 3 and bolster guide columns 4 spacing intermediate portions thereof and spaced to leave a window opening 5 therebetween. In the present embodiment, the side frame illustrated is of the type described and claimed in my Patent Number 1,652,808 of December 13, 1927, on a car truck, but it is obvious that I do not wish to be limited to the embodiment of this invention with such a type of frame, the showing being preferred but not limiting.

As more fully described in my prior patent, the side frame 1 involves auxiliary tension members 6 which cut across the lower corners of the window or bolster opening 5 and form upwardly extending convolutions which strengthen the frame and serve for interlocking the spring plank 7 with respect thereto, said spring plank being for that purpose provided with corresponding upwardly extending convolutions or corrugations 8. It will be noted that the width of said auxiliary tension members 6 and the corresponding corrugations 8 in the spring plank is less than that of the spring supporting portion of the tension member and preferably

corresponds with the diameter of one of the bolster springs 9 as shown in Figure 2. The auxiliary tension members also preferably terminate by merging with the spring supporting portion of the tension member short of the center thereof whereby a central flat spring supporting area is left for the central spring unit 10 of the nest of springs. Upon referring to Figure 4 it will be seen that a preferred spring grouping involves seven spring units arranged as two rows of three spring units disposed on either side of the auxiliary tension member 6 and a single spring unit disposed between said rows and between the central springs of said rows, giving a nest of springs substantially H-shape in plan, the auxiliary tension members 6 fitting between the ends of the uprights of said H, whereby the horizontal or spring supporting area of the tension member is efficiently utilized for the purpose. Alternative spring arrangements may be employed, if desired, some of which are disclosed in my Patent Number 1,652,808, referred to.

Spring plates 11 and 12 constructed as disclosed in said patent may be employed, although I do not wish to be limited to such details. Resting on the tops of the springs or top spring plate 12, if used, is a spring cap 13 which in the present embodiment is articulated or formed as two parts, a lower part 14 which rests directly on the springs or upper spring plate and an upper part 15 which rests on the lower part 14 and is arranged to rock thereon in a vertical longitudinal plane.

The lower spring cap portion 14 is preferably adapted to serve for interlocking the associated bolster 16 with respect to the frame and for that purpose is preferably provided with outwardly extending flanges 17 and 18 embracing the adjacent or bolster guiding portions of the columns 4 and adapted for vertical movement with respect thereto while interlocking the cap against longitudinal and transverse movements.

The rear or inner flanges 18 are preferably reduced in height in order to facilitate insertion of the spring cap in the widened lower portion of the bolster opening above the auxiliary tension members 6. The column engaging flanges 17 and 18 are preferably joined by a web 19, which web is continued around the front end of the upper portion of the spring cap and associated bolster, reduced in height so as not to interfere with the bolster, and continued around the rear or inner end of said upper portion 15 of the spring cap. For strengthening the construction, the front and rear portions of the web 19 are rigidified with respect to the lower or spring engaging web 20 of the spring cap portion 14 by means of substantially triangular gusset portions 21. The periphery of the lower web 20 of said member is preferably provided with a

depending flange 22 extending over and embracing the upper ends of the bolster springs 9 to assist in maintaining them in proper position. The upper surface of the web 20 between the parts of the web 19 is preferably curved or crowned longitudinally of the frame for permitting longitudinal rocking in a vertical plane between the upper and lower portions of the spring cap 13.

10 The upper portion 15 of the spring cap is formed with a lower web 23 which is preferably flat and rests directly on the crowned or curved web 20 of the lower portion 14 of the spring cap whereby longitudinal rocking 70 therebetween in a vertical plane is permitted. Immediately adjacent and between the bolster guide columns 4 the spring cap portion 15 is provided with upwardly opening depressed pocket portions 24 which fit in corresponding apertures 25 in the lower spring 75 cap portion and provide depressed bearing portions for receiving lateral motion rockers 26. In the present embodiment the lower walls of the pockets 24 are flat and the lower 80 surfaces of the rockers 26 are curved laterally of the frame, said curvature, however, being greater inwardly of the truck than outwardly thereof for a purpose to be more fully explained hereinafter. The upper ends of the 85 rockers 26 are preferably formed in a similar but reverse manner, that is, the curvature outwardly of the frame is greater than the curvature inwardly thereof and the associated bolster 16 is preferably provided with 90 a downwardly opening pocket 27, the upper wall of which forms a rocker bearing which is preferably flat and horizontal. 95

In order to maintain the desired relation 100 between the bolster 16 and the rockers 26, as well as to make it impossible to put the rockers in upside down, the upper end of each rocker is preferably formed with a tooth or lug 28 engaging in a corresponding pocket 29 in the bolster. A corresponding interlocking 105 arrangement may be provided between the lower ends of the rockers and the upper spring cap portion 15 but inasmuch as said rockers are fairly closely received in the depressed pocket portions thereof, such is not 110 considered necessary in the present instance. In order, however, to prevent the misapplication 115 of the rockers 26 in the pockets 24 an intermediate portion of each rocker is preferably narrowed or cut away as indicated at 120 30 to provide pockets for interlocking with corresponding bosses 31 on the sides of the pockets 24. On account of this construction it will be obvious that said rockers can only be applied in the pockets 24 in the proper 125 manner, as reversal thereof about a vertical axis is impossible due to the interlocking between the pockets 30 and the bosses 31 and reversal about a horizontal axis is impossible because of the interlocking between the 130 tooth 28 and the pocket 29.

The lower web 23 of the portion 15 of the spring cap is preferably provided with an upstanding peripheral flange 32 which extends around the sides and front thereof but is omitted at the rear to provide for the reception of the associated bolster 16. The side portions of the flange 32 lie closely adjacent the corresponding portions of the web 19 as well as the corresponding sides of the bolster and in order to permit the vertical angling between the parts of the spring cap, the adjacent or inner surfaces of the web 19 are preferably correspondingly crowned or curved as illustrated to provide the proper clearance for rocking. The bolster is preferably of such length that the front or outer portion of the flange 32 serves as a limit stop therefor and it will be apparent that on account of the difference in curvature between the outer and inner portions of the rockers 26 the end of the bolster is raised when moved outwardly to a greater extent than when moved inwardly. If, as is preferred, the portions of the rockers of greater curvature are concentric and the center of curvature of the remaining upper portion is below the center of curvature of the remaining lower portion, then the bolster will be raised when moved outwardly and maintained at the same elevation upon inward movement. A preferred construction of the rockers provides for raising of the bolster $\frac{1}{4}$ inch upon outward lateral movement of 1 inch while the bolster is not raised or lowered upon inward movement thereof. 100

Referring now to the modification of my invention illustrated in Figs. 5, 6 and 7, a side frame 1^a is there disclosed which is formed with a compression member 2^a, bolster guide columns 4^a and a tension member, not shown, defining a window opening 5^a therebetween as in the previous embodiment. Although the frame is only fragmentarily illustrated, it will be understood that it may be, and preferably is, identical with the frame of the first embodiment and the bolster springs 9^a and 10^a are supported in the same manner. 105

Resting on the springs 9^a and 10^a or the upper spring plate 12^a, if used, is a spring cap 13^a formed with outstanding flanges 17^a and 18^a which embrace the adjacent portions of the guide columns and hold the cap in proper relation with respect to the frame—while permitting up and down movement thereof with variation in the load on the supported bolster 16^a. In the present embodiment the spring cap is formed as a single casting rather than two castings with provision for rocking therebetween, said casting involving a lower web or wall 20^a, provided with a depending peripheral flange 22^a which extends over and embraces the upper ends of the springs 9^a and serves to hold them in proper assembled relation. 110

The lower web 20^a of the spring cap, which 115

is preferably ribbed for strength on its upper surface, as illustrated most clearly in Figure 7, is depressed or pocketed downwardly adjacent the bolster guide columns as in the previous embodiment to provide pockets 24^a, which are preferably provided with an aperture near the bottom thereof, as illustrated, to facilitate cleaning, the lower walls of which form bearings for the lower ends of 10 associated rockers 26^a. The outer walls 19^a of said pockets form the connecting web between the flanges 17^a and 18^a and are continued around the front or outer portion of the casting at reduced height as a depending 15 peripheral flange 22^a previously referred to and around the back in the same manner except that the depth, in the present embodiment, is slightly greater. As in the previous embodiment, the spring cap is provided with 20 an upstanding web or flange 32^a serving as an auxiliary bolster limit stop, said bolster being additionally provided with inner guiding lugs 33 adapted to engage the inner sides of the bolster guide columns upon maximum 25 outward movement thereof. As in the previous embodiment the limiting flange 32^a is braced with respect to the web 22^a by means of triangular gussets 21^a.

The rockers 26^a in the present embodiment 30 are of somewhat different character from those in the first embodiment in that they are relatively larger or taller and are substantially triangular in side elevation, the small, pointed or rounded end 34 extending downwardly into the corresponding bearing pocket 24^a and adapted to swivel therein in a vertical transverse plane or, if desired, rocking therein as in the previous embodiment. In order to prevent misapplication of the rockers 26^a in the bearing pockets 24^a one side 35 of the lower end 34 is narrowed or cut away as indicated at 30^a in order to fit between corresponding bosses 31^a on the inside of the pocket. As in the previous embodiment the 40 bolster is provided with downwardly opening pockets 27^a for receiving the upper or flaring ends of the rockers 26^a, the inner walls of said pockets being formed with teeth or 45 bosses 28^a interlocking in corresponding notches 29^a in the sides of the rockers 26^a. As in the previous embodiment the curved 50 upper sides of the rockers 26^a are preferably so designed that the bolster is raised slightly upon outward movement thereof and maintained at the same elevation upon inward 55 movement of said rockers.

Referring now to the embodiment of my invention illustrated in Figs. 8, 9 and 10, a construction is there disclosed in which a lateral motion bolster embodying my invention is combined with a side frame having carrier rings journaled therein for limited rotation in a vertical longitudinal plane. A frame of 60 this character is disclosed in Patent Number 65

1,594,576 to H. D. Taylor, entitled Car truck, dated August 3, 1926.

The side frame 1^b is only diagrammatically illustrated and in lieu of a bolster opening of conventional character between a compression member 2^b, a tension member 3^b and guide columns 4^b, said parts define a circular bolster opening 5^b. Mounted or journaled in said circular opening is a carrier ring 35 adapted to have limited swiveling motion 70 in a vertical longitudinal plane with respect to said frame. Said carrier ring 35 may be locked against removal after application in any desired manner as by means of keys 36 engaging notched edges of said carrier ring and held in place between spaced portions 75 of the bolster guide columns 4^b by means of bolts or the like 37. The lower portion of the carrier ring 35 is formed with a segmental portion 38, the upper surface of which is flat 80 and adapted to support the associated spring plank 7^b.

Resting on said spring plank or associated 85 spring plate 11^b are bolster springs 9^b, said springs in the present embodiment forming a five-unit nest of springs, the inner and outer rows of which define spaces separated by the central spring unit 10^b which serve for 90 permitting the use of a spring cap 13^b resting on said springs or an upper spring plate 12^b with depressed rocker receiving pockets 24^b as in the first embodiment. The sides of the carrier ring 35 are formed with vertical 95 segmental portions 39 which function as bolster guiding portions and are engaged by outwardly extending flanges 17^b and 18^b as in the first embodiment, said flanges being joined by webs 19^b which serve as outer or end walls 100 of the rocker receiving pockets 24^b in the spring cap 13^b.

As in the previous embodiment the spring 105 cap 13^b is preferably formed with depending peripheral flanges 22^b which embrace the upper ends of the springs 9^b and tend to hold them in proper position. For strengthening 110 the construction of the spring cap 13^b the upper web 20^b is preferably ribbed as illustrated like the previous embodiment. For interlocking 115 the bolster with respect to the spring cap 13^b for limiting the movement therebetween, 115 said bolster is preferably notched as indicated at 40 to receive the flanges 17^b and 18^b and the connecting web 19^b.

The provision for lateral motion between 120 the bolster and spring cap may correspond with that of the first embodiment except that the spring cap is formed in one piece as in the second embodiment with no provision for angling in a vertical longitudinal plane, such provision being obviously unnecessary on account of the provision for such angling of the carrier ring 35 with respect to the frame 1^b. That is, the lower walls of the pockets 24^b are 125 preferably flat and rockers 26^b corresponding in shape with the rockers 26 of the first em- 130

bodiment are received therein and operate in a similar manner, both with respect to the spring cap and the associated bolster 16^b. The upper surface of the end of the bolster is preferably curved to correspond with the curvature of the carrier ring 35 to facilitate insertion and removal while at the same time efficiently providing for adequate depth.

From the foregoing it will be apparent that I have devised a truck in which provision is made for transverse movement of the bolster about rockers held in supporting spring caps, and, if desired, provision may also be made for angling between the bolster and associated side frames in vertical longitudinal planes.

Although one end only of the bolster and its associated side frame and parts are illustrated, it will be obvious that the other end of the bolster and the other side of the frame is correspondingly formed. The lateral motion rockers are preferably held in depressed pockets, space being economized by providing said pockets immediately over auxiliary inclined tension portions of the frame where such a frame is used or between laterally spaced springs. In order to make the bolster self-centering, as well as to secure desirable results with respect to movement of the center of gravity of the associated car body, the rockers are preferably designed to raise the end of the bolster which moves outwardly and retain the other end at substantially the same elevation. In one form of the invention there is disclosed how to provide that the load from the bolster shall remain substantially on the center line of the spring group, such a result being obviously desirable so as to stress the bolster springs uniformly.

Although lateral motion devices of a specific character have been disclosed in the preferred embodiments of my invention, I do not wish to be limited to such a showing, as other lateral motion devices besides rockers, for example, rollers, may be employed within the spirit and scope of my invention, while still accomplishing some of the objects thereof.

Having now described my invention, I claim:

1. A railway truck having side frames formed with compression and tension members, each frame having bolster guide columns connecting intermediate portions of said members, bolster springs disposed between said columns, a spring cap formed with pockets spaced by one of said springs and disposed immediately adjacent and between said columns, rockers in said pockets, and a bolster supported on said rockers and adapted to move laterally thereon.

2. A railway truck having side frames formed with compression and tension members, bolster guide columns connecting intermediate portions of said members, bolster springs disposed between said columns, a

spring cap formed with openings immediately adjacent and between said columns, a supplemental member supported on said spring cap and adapted to rock longitudinally thereon, said member having depending pockets fitting in said openings, rockers in said pockets, and a bolster supported on said rockers and adapted to move laterally thereon.

3. A railway truck having side frames formed with compression and tension members, bolster guide columns connecting intermediate portions of said members, bolster springs disposed between said columns, a spring cap formed with pockets adjacent and between said columns, said spring cap being mounted to angle in a vertical longitudinal plane, rockers in said pockets, and a bolster supported on said rocker and adapted to move laterally thereon.

4. In a railway truck, a side frame comprising a compression member, a tension member, bolster guide columns interposed therebetween and spaced to leave a window opening, that portion of the frame adjacent the junctions between the bolster guide columns and tension member being reinforced by auxiliary diagonal tension members which cut across the lower corners of the window opening and are narrower than the adjacent portions of the tension member, bolster springs disposed on either side of and between said auxiliary members, a spring cap resting on said springs and formed with upwardly opening pockets directly over said auxiliary tension members, rockers operating in said pockets, and a bolster supported on said rockers and adapted to move laterally thereon.

5. In a car truck, a side frame comprising a compression member, a tension member, bolster guide columns interposed therebetween and spaced to leave a window opening, the construction adjacent the junctions between the bolster guide columns and tension member being reinforced by auxiliary diagonal tension members which cut across the lower corners of the window opening, bolster springs supported on the tension member on either side of and between said auxiliary members, a spring cap resting on said springs and formed as two parts adapted to angle in a vertical plane with respect to each other, said spring cap being formed with pockets disposed over said auxiliary tension members, rockers in said pockets and a bolster supported on said rockers for lateral movement thereon.

6. In a railway truck in combination, a side frame formed with a compression member, a tension member, bolster guide columns interposed therebetween and spaced to leave a window opening, the tension member between the bolster guide columns being laterally widened for supporting bolster

springs, the junctions between said tension member and bolster guide columns being reinforced by auxiliary diagonal tension members of less width than the spring supporting portion of the tension member which cut across the lower corners of the window opening and restrict the horizontal area of the spring supporting portion of the tension member, bolster springs supported on said horizontal spring supporting portion of the tension member on either side of and between said auxiliary tension members, a spring cap supported on said bolster springs and provided with depressed rocker receiving pockets immediately over the auxiliary tension portions, whereby they do not interfere with the bolster springs, rockers in said pockets, and a bolster provided with upper rocker bearings supported on said rockers for lateral movement with respect to said frame.

7. A railway truck having side frames each formed with a window opening, bolster springs disposed in said window opening, a spring cap interlocked with the frame at each side of the opening, formed with spaced pocketed portions immediately adjacent said sides as well as means limiting lateral movement of the bolster, rockers in said pockets, and a bolster supported on said rockers and adapted to move laterally thereon.

8. A railway truck having side frames each formed with a window opening, bolster springs disposed in said opening, a spring cap comprising a lower member formed with apertures immediately adjacent the sides of said window opening, an upper member supported on said lower member and adapted to rock longitudinally thereon, said upper member having depending pocketed portions fitting in said apertures, rockers in said pocketed portions, and a bolster supported on said rockers and adapted to move laterally thereon.

45 9. A railway truck having side frames each formed with a window opening, a spring plank and bolster springs disposed in said opening, a spring cap mounted to angle in a vertical longitudinal plane with respect to said frame and formed with pockets depending below the tops of the springs adjacent the sides of said opening, lateral motion devices in said pockets, and a bolster supported thereon.

55 10. In a railway truck, a side frame formed with a window opening, said frame being reinforced by auxiliary diagonal tension members which cut across the lower corners of the window opening and are narrower than the adjacent portions of the frame, bolster springs disposed to embrace said auxiliary members, a spring cap resting on said springs and formed with upwardly opening pockets depressed over said auxiliary tension

members, lateral motion devices in said pockets, and a bolster supported thereon.

11. In a car truck, a side frame formed with a window opening, the construction adjacent the lower portion being reinforced by auxiliary diagonal tension members which cut across the lower corners of the window opening, bolster springs supported on the tension member on either side of and between said auxiliary members, a spring cap resting on said springs and formed as two parts adapted to angle in a vertical plane with respect to each other, said spring cap being formed with pockets disposed over said auxiliary tension members, lateral motion devices in said pockets and a bolster supported thereon.

12. In a railway truck in combination, a side frame formed with a window opening, the frame beneath the window opening being laterally widened for supporting bolster springs, the ends of said widened portion being reinforced by auxiliary diagonal tension members, of less width than said spring supporting portion, which cut across the lower corners of the window opening and restrict the horizontal area of the spring supporting portion, bolster springs supported on said horizontal spring supporting portion to embrace said auxiliary tension members, a spring cap supported on said bolster springs and provided with depressed rocker receiving pockets immediately over the auxiliary tension portions, whereby they do not interfere with the bolster springs, lateral motion devices in said pockets, and a bolster provided with upper bearings supported on said devices.

13. A railway truck having side frames formed with compression and tension members, bolster guide columns connecting intermediate portions of said members, bolster springs supported by means of said tension member between said columns with at least one of said springs aligned with said columns, a spring cap formed with a depressed pocket between said columns in space left by said aligned spring, a rocker in said pocket, and a bolster supported on said rocker and adapted to move laterally thereon.

14. A railway truck having side frames each formed with a window opening, bolster springs disposed in said window opening, a spring cap interlocked with the frame at each side of the opening and formed with spaced pocketed portions immediately adjacent said sides, lateral motion devices in said pockets, and a bolster supported on said devices and adapted to move laterally thereon, said devices being so constructed that the bolster is raised at the end which is moved outwardly and maintained at substantially constant elevation at the other end.

15. A railway truck having side frames formed with compression and tension mem-

bers, bolster guide columns connecting intermediate portions of said members, bolster springs disposed between said columns and supported by means of said tension member, 5 a spring cap supported on said springs between said columns and formed with a pocket aligned with said columns and at least one of said springs, a lateral motion device in said pocket, and a bolster supported on said device 10 said lateral motion device being so constructed that the bolster is self-centering.

16. A railway truck having side frames formed with compression and tension members, bolster guide columns connecting intermediate portions of said members, bolster springs disposed between said columns, a 15 spring cap formed with spaced pocketed portions between said columns, rocker means in said pocketed portions, and a bolster supported on said rocker and adapted to move laterally thereon.

In testimony whereof I affix my signature.

DONALD S. BARROWS.
